Cooper, Kerr & Dunham.

UNITED STATES PATENT OFFICE.

ASA E. MOON, OF SCRANTON, PENNSYLVANIA.

DEVICE TO DETERMINE SIZE OF YARN PACKAGES.

Application filed September 21, 1926. Serial No. 136,751.

This invention pertains to machines such as winders, spoolers, twistlers, coners, tubes, and other machines in which yarn or thread is wound into packages.

5 In such apparatus the package is usually formed by winding the yarn on a spool. For trade purposes it is desirable to have the packages of predetermined uniform dimensions.

10 Heretofore it has been customary to rely on the operator or attendant to determine by observation when each spool has been wound to the proper diameter but the results have never been satisfactory. The attendant has a great number, sometimes hundreds, of spindles under his charge and it is impossible for him to stop each one at exactly the right instant. The result has been that the packages are not uniform, which often 15 causes trouble in subsequent operations, such as packing.

Also, it has not been possible to furnish a number of packages each containing the same number of yards of yarn. Also, the 20 present methods do not permit the operation of the machines to their full capacity because so much time is lost on account of the inability of the operator to be in more than one place at once.

25 Various devices have been devised in the effort to mechanically limit the size of such packages to desired dimensions, but they have not been successful. Some of them have had arms or fingers constantly in contact with the yarn or thread, either before or 30 after it is wound, which is often injurious to the yarn.

35 Other devices have been worked out to "snub" the yarn when it reached a certain point. Such devices are only practical on fine, easily broken threads but are not practical on material which offers any appreciable resistance to rupture.

The object of my invention is to provide 40 a device which overcomes all the above objections, which is entirely out of contact with the yarn until the package has acquired the desired diameter, and which cuts the 45 yarn or thread when that diameter is reached, instead of rupturing the yarn by snubbing it. My device is equally effective

on fine delicate yarn or on heavy coarse threads.

Another object is to provide a device which is easily adjustable for packages or 55 spools of different diameters.

Further and other objects and advantages will be hereinafter set forth in the accompanying specification and claims, and shown in the drawings, which by way of illustration show what is now considered to be the preferred embodiment of the invention.

Fig. 1 is a side view of the device in operative position on the machine.

Fig. 2 is a plan view of Fig. 1.

Fig. 3 is an enlarged view of the front of the device.

Fig. 4 is a plan view of the device, showing in full lines the normal position of parts, and showing in broken lines the parts in 70 moved position.

Fig. 5 is an enlarged view of the head of the device, taken from the side.

Referring to Figs. 1 and 2, 10 is a fixed part of the frame of a machine such for 75 instance as a spooler. 12 is a spool upon which is being wound the thread or yarn 14 to form the package which it is desired to limit to a predetermined size or diameter. Spool 12 is mounted on a spindle 16, to 80 which is fast a pulley 18 driven by a belt 20, in a counterclockwise direction (Fig. 2).

The thread guide rod 22 is raised and lowered by the vertically reciprocating lifter rods 24. Fast to guide rod 22 is the thread 85 guide 26. A tension device 28 is provided to maintain uniform tension in the yarn.

In operation, spindle 16 rotates spool 12 in the direction of the arrow, thus drawing thread 14 from the source of supply 90 through tension device 28. Guide rod 22 at the same time reciprocates vertically to cause the thread to wind evenly from one end of the spool to the other.

All the above described mechanism is old 95 and well known. It has been described simply to make perfectly clear the operation of the present invention which will now be described.

Attached to frame 10 is a fitting 30. This 100 fitting is provided with a slot 32, through which passes locking bolt 34. The slot pro-

vides a means for adjusting the device lengthwise of the machine.

Arising from fitting 30 and fast thereto is the vertical bracket 36. Pivotally mounted at the upper end of bracket 36, on vertical pin 38, is the laterally extending blade 40, provided with two ears 42 through which passes the pivot pin 38. The same end of blade 40 is bent to form angle piece 44 to which is fastened one end of coil spring 46 the purpose of which will later appear.

Mounted on the front of plate 40 is a somewhat similar plate 50, provided with a tail piece 52 which passes through slot 54 in plate 40. The free end of 52 rests against the inner end of adjusting screw 54 threaded through bracket 36.

Plates 40 and 50 are held together by stud 56 which passes snugly through a hole in plate 50 and through a slot 58 (Fig. 3) in plate 40. This arrangement permits plates 40 and 50 to slide horizontally relatively to each other. To the front end of stud 56 is attached the other end of spring 46.

The free ends of plates 40 and 50 are notched to form a narrow V shaped slot 60 when the plates are in normal position as in Fig. 3. The lower portion of the notch in plate 40 is shaped as at 62 to connect one side of slot 60 to the bottom outer corner of plate 40.

With the above description in mind the operation of the device will be readily understood.

The device is located by means of slot 32 so that when the package or spool has attained the desired diameter, thread 14 contacts with the outer end of blade 40. This will be understood from Fig. 2, from which it will be seen that after one more wrap has been added to the package, contact will take place. This contact limits the size of the package, as will be seen.

Due to the action of guide rod 22, the yarn 14 constantly traverses the spool 12 vertically from end to end. When the winding on the spool reaches a predetermined diameter, the thread, while passing upwardly, will contact with the under side of surface 62 as indicated in Fig. 3, and as guide rod 22 rises beyond that point the thread will be guided by surface 62 into slot 60 wherein the thread wedges. After the thread is wedged in slot 60, the continued rotation of spool 12 swings plates 40 and 50 from normal position, indicated by lines in Fig. 4, towards the position indicated by broken lines in that same figure. It will be noted that the blades 40 and 50 swing about different centers, plate 40 swinging about pin 38 and plate 50 swinging about the outer end of tail piece 52. This means that plate 50 slides outwardly with reference to plate 40 as shown in the broken lines in Fig. 4,

thereby causing a shearing action at slot 60 65 and cutting the thread.

In actual service the action of the device is practically instantaneous after the thread contacts with surface 62, and it cuts large strong threads as readily as fine delicate 70 yarns.

In practice it is customary to slightly bevel the cutting edges at slot 60, but that is not necessary. The width of slot 60 may be regulated by means of screw 54 which moves 75 plate 50 relatively to plate 40.

The amount of movement of the plates relatively to each other is limited by the length of slot 58.

Spring 46 returns the parts to normal position 80 against stop 64 (Figs. 3 and 5) after a cutting operation has taken place.

It is to be understood that the invention is not limited to the construction herein specifically illustrated but can be embodied in 85 other forms without departing from its spirit.

I claim—

1. In a machine of the class described, in combination with means for winding yarn 90 to form a package, means operable by the yarn before it is wound on the package for cutting said yarn when the package attains a predetermined size.

2. In a yarn winding apparatus, in combination with means for winding yarn onto a spool to form a package, a yarn cutting device, and means for guiding said yarn into said cutting device when the package has attained a predetermined diameter. 100

3. In a yarn winding apparatus, in combination with means for winding yarn onto a spool to form a package, a yarn cutting device, means for guiding said yarn into said cutting device when the package has attained a predetermined diameter, and means thereupon responsive to the movement of the yarn for actuating said cutting device to sever said yarn. 105

4. In a yarn winding machine, the combination of a spool, means for revolving said spool to cause a strand of yarn to be wound thereon, a reciprocatory yarn guide adapted to carry the yarn back and forth across the face of said spool to effect a desired distribution thereon, and a device established in the path of the yarn as it travels with the yarn guide for cutting said yarn when a predetermined quantity thereof has been wound upon the spool. 110

5. The invention set forth in claim 4, in which said cutting device is actuated by the yarn itself. 120

6. In a yarn winding machine, the combination of a spool, means for revolving said spool to cause a strand of yarn to be wound thereon, a cutting device actuated by frictional engagement with the yarn, and means

for guiding the yarn into engagement with said cutting device when a predetermined quantity of yarn has been wound upon said spool.

5 7. In a machine of the class described, in combination, means for winding yarn to form a package, a device responsive to the movement of the yarn before it is wound

on the package for cutting the yarn when the package has attained a predetermined size, ¹⁰ and means for adjusting said cutting device to produce packages of different sizes at the will of the operator.

In testimony whereof I hereto affix my signature.

ASA E. MOON.
